UNITED STATES PATENT OFFICE

172,055

PHOTOFFLASH REFLECTOR

Robert L. Pennock, Jr., Denver, Colo., assignor to
Heiland Research Corporation, Denver, Colo., a
corporation of Colorado

Application April 10, 1953, Serial No. 24,444

Term of patent 14 years

(Cl. D61—1)

To all whom it may concern:

Be it known that I, Robert L. Pennock, Jr., a citizen of the United States, residing at Denver, in the county of Denver, State of Colorado, have invented a new, original, and ornamental Design for a Photoflash Reflector, of which the following is a specification, reference being had to the accompanying drawings, forming part thereof, and wherein:

Figure 1 is a front elevational view of a photoflash reflector showing my new design;

Figure 2 is a side elevational view thereof;

Figure 3 is a rear elevational view thereof; and

Figure 4 is a top plan view thereof.

I claim:

The ornamental design for a photoflash reflector, as shown.
